UNITED STATES PATENT OFFICE.

JOHN W. BELL, OF DENNYSVILLE, MAINE.

DESIGN FOR A RACK FOR HOLDING ARTICLES.

No. 40,061.

Specification for Design.

Patented June 15, 1909.

Application filed December 30, 1908. Serial No. 470,115. Term of patent 14 years.

To all whom it may concern:

Be it known that I, JOHN W. BELL, a citizen of the United States, residing at Dennysville, in the county of Washington and State of Maine, have invented a new, original, and ornamental Design for a Rack for Holding Articles, of which the following is a specification.

Reference is had to the accompanying drawing, in which:—

Figure 1 is a perspective view of a rack for

holding articles, showing my new and ornamental design. Fig. 2 is a plan view of the same.

I claim:—

The new and ornamental design for a rack for holding articles, as shown.

JOHN W. BELL.
